US00D957792S

(12) **United States Design Patent** (10) **Patent No.:** **US D957,792 S**
(45) **Date of Patent:** **** Jul. 19, 2022**

(54) **MULTIPURPOSE ARTICLE**

(71) Applicant: **Kathleen McKenna-Schliep**,
Huntington Beach, CA (US)

(72) Inventor: **Kathleen McKenna-Schliep**,
Huntington Beach, CA (US)

(**) Term: **15 Years**

(21) Appl. No.: **29/748,017**

(22) Filed: **Aug. 26, 2020**

(51) **LOC (13) Cl.** **02-02**

(52) **U.S. Cl.**

USPC **D2/864; D3/233**

(58) **Field of Classification Search**

USPC D2/864; D3/232, 233

CPC A41D 15/04; A41D 13/04

See application file for complete search history.

(57) **CLAIM**

The ornamental design for a multipurpose article, as shown and described.

DESCRIPTION

FIG. 1 is a front perspective view of a multipurpose article showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 shows the multipurpose article in a first state, in which the multipurpose article is used as an apron;

FIG. 9 shows the multipurpose article in a second state, in which the multipurpose article is used as a handbag;

FIG. 10 shows the multipurpose article in a third state, in which the multipurpose article is used as a shoulder bag; and,

FIG. 11 shows the multipurpose article in a fourth state, in which the multipurpose article is used as a floral bouquet wrap.

The broken lines depict environmental matter that forms no part of the claimed design.

1 Claim, 11 Drawing Sheets
